UNITED STATES PATENT OFFICE.

JOHN J. DAHLSTROM, OF AMITE, LOUISIANA.

FOLDING CRATE.

1,120,693.

Specification of Letters Patent.

Patented Dec. 15, 1914.

Application filed July 26, 1913. Serial No. 781,422.

To all whom it may concern:

Be it known that I, JOHN J. DAHLSTROM, a citizen of the United States, residing at Amite, Tangipahoa parish, Louisiana, have 5 invented certain new and useful Improvements in Folding Crates, of which the following is a specification.

This invention relates to improvements in folding crates, and its object is to provide a crate of extremely simple construction which may be manufactured and sold at small cost; which may be readily and quickly set up or dismantled; which, when set up, is substantial and not liable to accidental collapse; which, when folded, is substantially flat and may be economically packed for storage or shipment; and which enables ready access to its contents for the purpose of inspection.

20 The improved crate comprises vertical hingedly connected walls, a top, and a bottom. The hinge connections between the vertical walls consist of members which are similar in form to staples and have parallel 25 vertical legs which form pivots for said walls and horizontal portions connecting said legs and extending diagonally across the corners of the adjacent walls, these horizontal portions serving to brace the walls 30 relatively to one another when the crate is set up and to maintain the relation of the top and bottom.

In the accompanying drawings: Figure 1 is a perspective view of a crate in which 35 the features of the invention are incorporated, the crate being set up for use. Fig. 2 is a longitudinal sectional view thereof. Fig. 3 is a plan view or edge elevation of the crate when collapsed. Fig. 4 is a 40 detail view showing one of the hinge connections between two of the vertical walls, the other hinge connections being of similar character. Fig. 5 is a detail view of a catch which aids in retaining the top against displacement.

Similar characters of reference designate corresponding parts throughout the several views.

The crate shown is of rectangular form 50 and has the vertical side walls 1 and the vertical end walls 2. The walls 1 and 2 are hingedly connected at their adjacent ends by generally U-shaped members 3 which have vertical legs 4 pivotally engaged with 55 the walls which said members connect and horizontal portions 5 connecting said legs

and, when the crate is set up, extending diagonally across the corners thereof. The hinge members are arranged at the upper and lower ends of the crate, the upper hinge members retaining the top 6 against upward, lateral, or endwise displacement and the lower hinge members forming supports for the bottom 7.

The top 6 and bottom 7 are structurally 60 independent of the vertical walls. When the crate is to be set up, the walls 1 and 2 are disposed at right angles to one another and the bottom 7 is placed in position. Said bottom braces the vertical walls at their 65 lower ends against accidental collapse and rests upon the horizontal portions 5 of the lower hinge members. The top 6 is provided with two or more transverse cleats 8 which project laterally from said top and 70 rest upon the upper edges of the side walls 1, thereby forming supports for the top. In order that the top may be held against displacement, its corner portions at one end thereof are engaged under the horizontal 75 portions 5 of the adjacent pair of upper hinge members. At the corners of the other end the top has oblique edges 10 which clear the horizontal portions 5 of the adjacent pair of upper hinge members and enable the 80 top to be quickly and conveniently placed in position. Between its oblique corner edges 10, the top is engaged by a catch 9 which is pivoted to the adjacent end wall of the box and, in connection with the upper 85 hinge members at the opposite end of the box, positively holds the top against displacement. When the top is to be removed, the catch 9 is swung on its pivot to a position clear of the top, at which time the removal of the top may be effected by canting 90 it slightly so as to raise the end which has the oblique edges 10, and then by sliding it longitudinally of the box until its corner portions at its opposite end are disengaged 95 from the adjacent hinge members. While the catch 9 may be of any suitable construction, it is preferably and economically made of wire, as shown in the drawings. Owing to the facility with which the top may be 100 removed and replaced, the contents of the crate may be readily inspected at any time. When the crate is to be collapsed, the top and bottom are taken from position and interposed between the side walls, parallel 105 thereto, after which the vertical walls are folded, so that the side walls are brought

as closely together as possible, as shown in Fig. 3. When folded, the crate takes up little space and may be economically packed for storage or shipment. When the crate is set up, the end walls fit between the side walls and the hinge members which provide diagonal connections between said end and side walls act as braces. In this way the crate, though simply constructed, is substantial and serviceable. The hinge connections are not liable to derangement, are cheap, and may be readily renewed, whenever the occasion may require.

Having fully described my invention, I claim:

A folding crate having vertical walls, hinge members connecting said walls at the upper and lower ends thereof, the hinge members comprising U-shaped members having vertical legs pivotally engaged with the walls which said members connect and horizontal portions connecting said legs, a

displaceable bottom which is supported on the horizontal portions of the lower hinge members when the crate is set up, and a displaceable top which has its corner portions at one end thereof engaged under the horizontal portions of the adjacent upper hinge members, when the crate is set up, the opposite corners of the top having inclined edges to clear the horizontal portions of the adjacent hinge members, and a catch pivoted to the end wall of the box adjacent that end of the top which has said inclined edges to engage over the top and prevent displacement thereof.

In testimony whereof I have hereunto set my hand in presence of two subscribing witnesses.

JOHN J. DAHLSTROM
